UNITED STATES PATENT OFFICE

2,464,417

VERTICALLY RECIPROCATING GYRATORY SCREEN

Lore Sandoz-Peter, Biel, Switzerland, assignor to Bulova Watch Co. Inc., New York, Succursale de Biel, Biel, Switzerland, a joint-stock company of Switzerland

Application August 30, 1946, Serial No. 694,082
In Switzerland October 22, 1945.

3 Claims. (Cl. 209—326)

1

The machine according to the invention is used to screen objects of different sizes, in particular watch jewels. It comprises, a series of superposed screens to which, simultaneously, gyratory motion and reciprocating motion in a vertical direction are imparted.

To obtain this result, in the preferred embodiment of the invention, the said screens are arranged on a tray mounted on the central element of a cardan suspension, which element is moved gyratorily by a rotary disk.

This disk revolves on one extremity of a shaft supporting the frame of the cardan suspension and to which shaft alternating rectilinear motion is imparted. The shaft slides in a guide-way within the frame and is longitudinally reciprocatingly moved by an eccentric revolvably supported by a shaft driving the disk which drives the central element of the cardan suspension.

The attached drawing represents, by way of example, an embodiment of the screening machine according to the present invention.

Fig. 1 is an elevation view partly in section;

Fig. 2 is an elevation view as seen at right angles to the view in Fig. 1. Certain parts along the line II—II in Fig. 1 are cut transversely.

With reference to the drawing, 1 denotes a frame having a base portion with a plate 2 by means of which the whole machine can be fixed to the work-bench, and a guide extending vertically from said base portion. A shaft 3 traverses and revolves within the base portion and has at one of its extremities a belt pulley 5. An eccentric 6 revolving on this shaft is driven by a second belt-pulley 7. This eccentric has a collar 8 to which a rod 9 is articulated, the latter being free to slide within a guide-way of the frame 1. By means of this arrangement, the rotary motion of pulley 7 is converted into a reciprocating motion of rod 9.

To the upper portion of rod 9 a base-member 10 is fixed forming part of support means for a cardan suspension.

This base member carries pillars 11 which serve as supports for the outer element 13 of the cardan suspension referred to above, this element being held between two pointed screws 12. The outer element 13 supports the inner element 15 by means of similar pointed screws 14. This latter element has the form of a sphere having two co-axial prolongations 16, 17. To prolongation 16 a tray 18 is fitted, and in a bore hole of prolongation 17 extends a pin 19 ending in a sphere 20 forming a ball-articulation with a

2

hollow socket in a disk 21 which revolves on the upper extremity of the shaft 9.

The disk 21 is provided with a belt groove 22 taking the means of transmission 23 which passes over the pulleys 5 and guide pulleys 24 pivoted at the extremity of an arm of the frame. In this way the motion of the driving wheel 4 is transmitted by the flexible belt 23 to the rotary disk 21.

The tray 18 is provided with guide-rods 28 arranged at 120° to one another, so as to form a frame into which the superposed screens 26 can be inserted upon a container 27 at the bottom. The size of the meshes of the different screens decreases from screen to screen, being bigger at the top and smaller at the bottom, whereby the objects placed in the uppermost screen will pass through one or more screens according to their sizes and will be retained in those having smaller meshes than the different sizes of the objects to be sorted out. Two screens only are shown in the drawing, but quite obviously any number could be used.

The rotary motion of pulley 4 is transmitted by a means of transmission 23 to the disk 21 which drives the central element 15 of the cardan suspension, imparting to it a gyratory motion which is transmitted to the tray 18 and consequently to the screens. Simultaneously, the pulley 7, connected to an independent source of power, drives the eccentric 6 which imparts a vertical reciprocating motion to the rod 9 which imparts it over the cardan suspension to the tray 18 and screens 26. The combined effect of the two kinds of motion agitates the objects contained on the screens briskly and causes them to pass from one screen to another until they are retained by the respective screens with meshes smaller in size than the outside dimensions of the differently sized objects.

What I claim is:

1. A screening machine for objects of different sizes, particularly for watch jewels, comprising, in combination, a vertical guide, a rod longitudinally slidably disposed in said guide and having a lower and an upper portion projecting therefrom, support means mounted on said upper portion, cardan suspension means connected to and supported by said support means and having a gyratorily movable inner element, a tray mounted on said inner element, superimposed screens placed on said tray, drive means comprising a reciprocatingly movable member connected with the lower portion of said rod and imparting a reciprocating up and down motion to said rod and the support means mounted thereon, a disk

rotatably supported inside said support means and having a surface portion facing said inner element, a spherical socket in said surface portion, a bore in said inner element, and a pin slideable in said bore and having a ball shaped end projecting from said bore and inserted in said socket and imparting a gyratory motion to said inner element and to the tray mounted thereon upon rotation of said disk.

2. A screen machine as defined in claim 1, comprising drive means connected to and rotating said disk and being independent from the drive means for said rod with respect to speed.

3. A screening machine for objects of different sizes, particularly for watch jewels, comprising, in combination, a base, a guide means extending upward from said base, a rod longitudinally slidably disposed in said guide means and having a lower and an upper portion projecting therefrom, support means mounted on said upper portion, cardan suspension means connected to and supported by said support means and having a gyroscopically movable inner element, a tray mounted on said inner element, superimposed screens placed on said tray, a shaft rotatably supported in said base, an eccentric revolvably mounted on said shaft and connected with the lower portion of said rod and imparting a reciprocating up and down motion to said rod and the support means

5 mounted thereon, a disk rotatably supported inside said support means and having a surface portion facing said inner element, a spherical socket in said surface portion, a bore in said inner element, a pin slideable in said bore and having a ball shaped end projecting from said bore and inserted in said socket and imparting a gyratory motion to said inner element and to the tray mounted thereon upon rotation of said disk, and flexible belt means interconnecting said shaft and said disk for driving the latter by the former.
